Primary Examiner—Caron D. Veynar*Assistant Examiner*—Ricky Pham(74) *Attorney, Agent, or Firm*—Wallenstein & Wagner, Ltd.(57) **CLAIM**

The ornamental design for an outer surface of a baker, as shown and described.

DESCRIPTION

FIG. 1 is a perspective view of an outer surface of a baker according to the new design;

FIG. 2 is a side elevation view of one side of the outer surface of the baker shown in FIG. 1, the other side being identical thereto;

FIG. 3 is a front view of the outer surface of the baker shown in FIG. 1, the rear view being identical thereto;

FIG. 4 is a top view of the outer surface of the baker shown in FIG. 1;

FIG. 5 is a bottom view of the outer surface of the baker shown in FIG. 1;

FIG. 6 is a perspective view of another preferred embodiment of a baker according to the new design;

FIG. 7 is a side elevation view of one side of the outer surface of the baker shown in FIG. 6, the other side being identical thereto;

FIG. 8 is a front view of the outer surface of the baker shown in FIG. 6, the rear view being identical thereto;

FIG. 9 is a top view of the outer surface of the baker shown in FIG. 6; and,

FIG. 10 is a bottom view of the outer surface of the baker shown in FIG. 6.

The broken lines shown in the drawings are for illustrative purposes only and form no part of the claimed design.
